(57) **CLAIM**

The ornamental design for a water timer as shown and described.

DESCRIPTION

FIG. 1 is a perspective view from above of a water timer, showing my new design;

FIG. 2 is a top view thereof;

FIG. 3 is a front side view thereof;

FIG. 4 is a left side view thereof;

FIG. 5 is a back side view thereof;

FIG. 6 is a right side view thereof; and,

FIG. 7 is a bottom view thereof.

Those portions of the figures shown in dotted lines form no part of our invention, but are included to show the context and environment of the invention.
